OXIDATION OF ORGANIC SULFIDES

Tor Halfdan Smedslund, Chicago, Ill., assignor to The Stepan Chemical Company, Chicago, Ill., a corporation of Illinois

No Drawing. Application March 27, 1956
Serial No. 574,073

2 Claims. (Cl. 260—607)

This invention relates to a method for the manufacture of sulfoxide, and more particularly, to an improved process for the manufacture of low molecular weight sulfoxides from the corresponding sulfides.

United States Letters Patent No. 2,581,050 relates to the vapor phase oxidation of dimethyl sulfide to dimethyl sulfoxide using an oxygen-containing gas which also includes a small amount of an oxygen-transmitting nitrogen oxide (such as NO_2), using reaction temperatures sufficient to maintain the dimethyl sulfide in the vapor phase.

United States Letters Patent No. 2,702,824 relates to the liquid phase oxidation of low molecular dialkyl sulfides to the corresponding sulfoxides by bubbling a gaseous mixture through the liquid dialkyl sulfide at a reduced temperature to maintain the dialkyl sulfide in the liquid phase. The gaseous mixture bubbled through the liquid dialkyl sulfide comprises an oxygen-containing gas and a small amount of an oxygen-transmitting nitrogen oxide.

In each of the foregoing operations, air is preferred as the oxygen-containing gas for obvious economic reasons. In carrying out these operations using air, however, prior to the instant invention it was found that the operating conditions were difficult to control and the yields obtained left something to be desired. The instant invention is based in part on the discovery that the use of pre-dried atmospheric air in the foregoing operations results in a distinct improvement in the yields and a distinct improvement in the control of the operating conditions. Compared to the quantities of other ingredients used the amount of moisture in atmospheric air is extremely small. Nevertheless, it has been found that this moisture in the air apparently has a very distinct harmful effect upon the reaction, and the instant invention contemplates the removal thereof from the air before carrying out the reaction. The instant invention also contemplates the use of substantially anhydrous sulfides in the reaction mixture, since it has also been discovered that the relatively small amount of moisture ordinarily present in the sulfides has a definitely harmful effect upon the reaction.

It is, therefore, an important object of the instant invention to provide an improved method for oxidizing low molecular weight sulfides to the corresponding sulfoxides.

It is a further object of the instant invention to provide an improved method for the manufacture of low molecular weight sulfoxides from the corresponding sulfides by an oxidation process which is made industrially superior by removal of moisture from the reactants prior to carrying out the oxidation reaction.

Other and further objects, features and advantages of the present invention will become apparent to those skilled in the art from the following detailed disclosure thereof.

The instant invention consists in a process for the manufacture of a low molecular weight sulfoxide from the corresponding sulfide by oxidation thereof, which comprises drying atmospheric air to reduce the relative

2

humidity thereof by at least one-half and then contacting the dried air with the sulfide in the presence of an amount of oxygen transmitting nitrogen oxide at least sufficient to catalyze the oxidation.

5 The sulfides which may be used in the practice of the instant invention include the low molecular weight dialkyl sulfides having the following formula:

10 wherein each R is the same or a different C_1-C_4 alkyl group. Such dialkyl sulfides include dimethyl sulfide, methyl ethyl sulfide, methyl propyl sulfide, methyl isopropyl sulfide, methyl n-butyl sulfide, methyl secondary butyl sulfide, etc.; diethyl sulfide, ethyl propyl sulfide, etc.; dipropyl sulfide, etc.; and dibutyl sulfide, etc.

15 The sulfides may also be heterocyclic compounds where S is a nuclear atom. Such compounds include 5 to 6 20 membered rings having 1 to 2 nuclear S atoms and the remainder C atoms, in saturated or unsaturated rings, with 1 to 2 substituents on the C atoms, preferably C_1-C_4 alkyl substituents. Typical types of compounds are based on the thiophene and tetramethylene sulfide 25 nuclei:

30 35 wherein each X is H or a C_1-C_4 alkyl group but not more than 2 X's are alkyl groups and the remainder are H's. Examples include tetramethylene sulfide, 1-methyl tetramethylene sulfide, 2-methyl tetramethylene sulfide, 1,3-dimethyl tetramethylene sulfide, etc. up to 1-butyl tetramethylene sulfide.

Another heterocyclic compound is based on a 6 membered ring nucleus:

40 45 wherein Y may be S or CX_2 and the X's have the meaning hereinbefore given. Examples include penta-methylene sulfide, 1-methyl pentamethylene sulfide, 2-methyl pentamethylene sulfide, 3-methyl pentamethylene sulfide, 1,2-dimethyl pentamethylene sulfide, etc. up to the butyl pentamethylene sulfides; and dithiane (i. e. di-ethylenic disulfide), 1-methyl dithiane, etc. up to the butyl dithianes. Members of these groups which are normally solids can be dissolved in, for example, dimethyl sulfoxide to provide a liquid composition of the sulfide that is oxidized in the process of the invention.

50 55 In the practice of the invention, the organic sulfide may be oxidized in either the liquid or the vapor phase, but in the case of the higher boiling sulfides it is ordinarily preferable to employ liquid phase oxidation at lower temperatures rather than at higher temperatures re-

60 65 quired to volatilize the sulfide. In general, sulfides boiling at temperatures above about 75° C . should be oxidized in the liquid phase rather than the vapor phase; and sulfides which are solids at temperatures above about 75° C . should be oxidized in the liquid phase in solution

70 75 in a sulfoxide such as dimethyl sulfoxide (or any other solvent which is not reactive with the ingredients here present, namely, the sulfide, sulfoxide, NO and NO_2). preferably, the aforementioned temperature of 75° C . should be about 40° C . since this is a preferred maximum temperature for carrying out the instant oxidizing reaction. The minimum temperature is, of course, around 10° C . or the minimum temperature at which

appreciable oxidation takes place. The preferred reaction temperature range is about 25-40° C.

The sulfides used in the practice of the instant invention are preferably substantially anhydrous. Although commercially available sulfides, which may contain as much as 0.5 or 1% by weight of moisture, may be used to advantage in the practice of the instant invention using dried air, still better results are obtained using the substantially anhydrous sulfide. The sulfide may be obtained in substantially anhydrous form (i. e., containing less than about 0.1% by weight of water) by passing the same in liquid or vapor form over a suitable drying agent, such as calcium oxide.

Although air at 80° F. having 50% relative humidity contains only about 0.01 pound of water per pound of air, this apparently insignificant amount of water has been found to be extremely harmful. In fact, it is possible to obtain a distinct advantage in the practice of the instant invention merely by reducing the relative humidity of the air by at least one-half of the initial relative humidity. Preferably, however, this reduction in relative humidity also results in a reduction of the moisture content in the air to below about 0.002 pound per pound of air. Best results are obtained if the moisture content is reduced to below about 0.001 pound per pound of air.

The humidity in the air may, of course, be reduced by passing the air through any sort of drier or dehumidifier. A preferred process involves passing the atmospheric air over calcium oxide, which effects a reduction in the moisture content to a relative humidity of approximately 1% at 100° F. (which is the moisture content of approximately 0.0005 pound per pound of bone dry air). The dehumidification of air is relatively easy and economic and for this reason very definite advantage from a practical point of view is obtained merely by drying the air, while using the commercial (undried) sulfide. In the vapor phase reaction, however, the air is used as a carrier for the sulfide to conduct the same into the reaction zone, and dehumidification of the air-sulfide vapor mixture can be carried out to advantage prior to reaction.

The amounts and types of oxygen-transmitting nitrogen oxides used in the practice of the instant invention are described in detail in said U. S. Patents No. 2,581,050 and 2,702,824 and need not be described with further particularity herein. Such gases include NO, NO₂, N₂O₃, N₂O₄, etc., but the predominating catalytic function is generally thought of on the basis of NO₂, as indicated in the following equations representing the reaction which is believed to take place:

wherein $>S$ is the sulfide S atom and $>S=O$ is the sulfoxide grouping. It will be noted that the actual oxidation of the sulfide to the sulfoxide is believed to be caused by reaction between the sulfide S atom and NO₂; but the resulting NO is instantly regenerated to NO₂ by the presence of the oxygen in the air. As will be appreciated, only a small amount of the oxygen-transmitting nitrogen oxide, such as about 10% to 15% by volume, is employed according to said U. S. Patent No. 2,702,824, and the bulk of the oxidizing gas is oxygen from the air which is added in an amount just sufficient to complete the oxidation of the sulfide.

Although it is not desired to limit the invention to any particular theory, it is now believed that the reason why such small amounts of water can produce such a noticeable effect upon the reaction is that the water apparently reacts with the NO₂ to form acids as indicated in the following equation:

The acids thus formed tend to condense out with the sulfoxide product and the concentration of catalyst is thus constantly being varied (in fact, reduced) during the

reaction. This causes difficulties in control of the reaction. In addition, the constant consumption of the catalyst requires the use of greater amounts of the nitrogen oxide than would ordinarily be required. Also, the acids formed must subsequently be neutralized in the sulfoxide product. It is further believed that the presence of the moisture actually interferes with the catalytic function so that lower yields of the sulfoxide are obtained.

As a demonstration of the instant invention, dimethyl sulfide is evaporated at a rate of 0.7 gram per minute into an air current of 680 milliliters per minute containing nitrogen dioxide introduced into the air current at a rate of 45 milliliters per minute. The resulting gaseous mixture is passed into the first of a series of four reaction chambers, each consisting of a glass tube 4.2 centimeters in diameter and 100 centimeters in length. The reaction starts immediately, the temperature of the reaction mixture reaches about 55° C. in the first reaction tube, about 45° C. in the second tube, about 36° C. in the third tube and about 25° C. in the last tube. The crude product contained traces of dimethyl sulfide and nitrogen dioxide, about 2% methane sulfonic acid and small amounts (i. e. about 0.3%) of water. In this demonstration, the air employed is first passed through a tube containing 200 grams of calcium oxide so as to reduce the relative humidity of the air to about 5% at 30° C.; but the dimethyl sulfide employed contained about 0.4% water. After purification (wherein the dimethyl sulfide was removed by heating the product to 150° C., the methane sulfonic acid was neutralized by adding slaked lime, and the dimethyl sulfoxide was distilled in vacuum) the yield of pure dimethyl sulfoxide was 91% of the theoretical yield. If the foregoing procedure is repeated using substantially anhydrous dimethyl sulfide (containing less than 0.1% moisture) a yield of 94% is obtained; but if atmospheric air at about 60% relative humidity is used with the undried sulfide the yield is only about 75% (and the reaction tube temperatures are 45° C., 40° C., 35° C. and 35° C. in that order). Partial drying of such atmospheric air to reduce the relative humidity by about one-half to 30% (at 30° C.) results in a distinct improvement in the yield to about 78%, although this is much less than the yield obtained by the use of substantially dried air.

As another demonstration, a single reaction chamber comprising a glass tube 4.3 centimeters in diameter and 50 centimeters in length is provided with a gas inlet at the bottom and a gas distributing plate. A charge of 500 grams of dimethyl sulfide was placed in the chamber, which was also filled with filling material near the bottom thereof to increase the reaction surface. The upper part of the reaction chamber is provided with a cooler maintained at minus 10° C. Air containing 12-15% NO₂ (which is volume percent based on the oxygen content of the air) is fed into the bottom of the chamber. The rate at which oxygen is thus fed into the bottom of the chamber is 6-10 liters per hour. As the reaction progressed the temperature was raised up to 40-45° C. and as the reaction was completed the temperature dropped back to room temperature. Using undried atmospheric air having a relative humidity of about 60% at 30° C. it was found that the yield obtained was about 80% of theoretical. Using air which has been dried to a relative humidity of about 1% at 30° C. (in the manner hereinbefore described), the yield obtained is about 90% of theoretical. If substantially anhydrous dimethyl sulfide is used instead of commercial grade, the yield is further increased to about 93% of theoretical.

It will be understood that modifications and variations may be effected without departing from the spirit and scope of the novel concepts of this invention.

I claim as my invention:

1. In a process for the manufacture of a di-lower alkyl sulfoxide from the corresponding sulfide by oxidation

thereof, which comprises contacting the sulfide with an oxidizing atmosphere containing air and an amount of oxygen transmitting nitrogen oxide at least sufficient to catalyze the oxidation, the improvement which comprises contacting the sulfide with air having a moisture content below 0.002 pound per pound of air.

2. In a process for the manufacture of a di-lower alkyl sulfoxide from the corresponding sulfide by oxidation thereof, which comprises contacting the sulfide in substantially anhydrous form with an oxidizing atmosphere con-

taining air and an amount of oxygen transmitting nitrogen oxide at least sufficient to catalyze the oxidation, the improvement which comprises contacting the sulfide with air having a moisture content below 0.002 pound per pound of air.
